UNITED STATES PATENT OFFICE.

STEPHEN HAINES PLUM, 2D, OF MADISON, NEW JERSEY, AND HARRY DUFF, OF BROOKLYN, NEW YORK, ASSIGNEES TO AMERICAN TYPE FOUNDERS COMPANY, A CORPORATION OF NEW JERSEY.

SUCTION NOZZLE FOR PRINTING PRESSES.

Original application filed August 14, 1924, Serial No. 731,910. Divided and this application filed June 23, 1926. Serial No. 117,919.

This invention relates to suction nozzles for printing presses. More particularly this invention relates to improvements in suction nozzles of the character disclosed in the 5 United States Patent Number 1,394,181 dated October 18, 1921, in connection with a Chandler & Price job printing press. This application is a division of the pending application Serial Number 731,910, filed August 14, 1924 10 now Patent No. 1,584,467.

As shown in said patent, the nozzle is mounted on an arm which is pivoted to the form member of the press, and as the press is operated, the nozzle is moved in over the 15 pile of stock to be printed to pick up the top sheet, which is thereafter conveyed to and placed onto the platen.

It is the object of this invention to provide an improved nozzle of the character shown in 20 the patent aforesaid, to which also reference is made for a complete disclosure of the operation of the nozzle. The invention is illustrated in the accompanying drawings in which

25 Fig. 1 is a diagrammatic view of a portion of a Chandler & Price job press showing the nozzle in position.

Fig. 2 is a side view of the nozzle shown in position on top of the sheets just prior to 30 the separation of the top sheet from the pile.

Fig. 3 is a similar view showing the nozzle in the position of having picked up the top sheet.

Fig. 4 is a view of the nozzle looking in 35 the direction of arrow 4 in Figure 3 and with parts omitted.

Fig. 5 is a detail view of the nozzle head shown in Figure 3.

Fig. 6 is a detail view of the nozzle support 40 shown in Figure 4.

Fig. 7 is a view in elevation of an adjustable extension nozzle embodying the invention.

Fig. 8 is a plan view of the nozzle head and 45 supporting bar shown in Figure 7.

Fig. 9 is a detail view of a modified form of nozzle head.

Fig. 10 is a side view thereof.

Fig. 11 is a plan view of still another form 50 of nozzle head.

Fig. 12 is a front view thereof.

Referring first to Figure 1 the press is identified as a typical Chandler & Price job press by the frame 1, platen 2 and form number 3. The paper stock 4 is supported on an auxiliary frame 5. To the form member is pivoted at 6 a bracket 7 which carries an arm 8 supporting a transverse rod 9 which carries the nozzle 10. 55

The details of construction and operation 60 of all of the foregoing parts are clearly disclosed in the above named patent to which reference is made for a full understanding thereof. Briefly, the operation is as follows: When the press closes as in Figure 1, the nozzle is positioned on the sheets 4 at the edge thereof. When the press opens, suction is applied by any well known means (not shown) and the top sheet is separated from the pile. As the press continues its opening movement, 70 the nozzle is moved to the right in the drawing in over the platen where the sheet is deposited at the proper time, the suction ceasing to function so as to release the sheet. In this brief description we have omitted reference 75 to a sheet conveying mechanism upon which the sheet may be placed, and which mechanism in turn conveys the sheet to the platen. In the said patent such a mechanism is shown and described. It is, however, obvious, that it 80 is immaterial whether the sheet falls from the nozzle onto the platen or onto some other mechanism so far as this invention is concerned. In order to understand the following description it will be sufficient to bear in mind 85 that the nozzle mechanism as such is carried on the aforesaid rod 9 which in turn is operated by the form member of the press.

Referring now to Figures 2, 3 and 4, the reference numeral 11 denotes a rather heavy 90 nozzle bracket which slides on the said rod 9 so as to be adjusted transversely of the press. A set screw 12 secures the bracket in position. The bracket has an upright portion 13 forming suitable guide ways 14, 14 in which slides 95 a nozzle support 15. The latter is in the form of a flat piece provided at its bottom with two ears 16, 16, while at the top there is formed a small lug 17 and a sleeve 18 is secured to the support. A thin rod 19 passes 100

through the lug and sleeve 18. At the top the rod 19 is provided with an adjusting nut 20 and a pin 21 is fitted into the rod to prevent rotation thereof. The support 15 also carries 5 a stop 22.

The nozzle head is of the gravity operated type, that is, the head 35 is pivoted at 36 in the ears 16 to tip downwardly to the left in the drawing. This movement is, however, 10 regulated by the spring 29. As shown in Figure 8, the rolling movement of the nozzle head is definitely limited by the stop 44 striking the stop edge 37 of a lug 36 secured to the nozzle support 15. The movement of the 15 bracket 11 downwardly as in Figure 2 is limited by an adjusting screw 39 provided with a clamping lever 40 which serves as a lock-nut. The adjustment of the screw 39 of course regulates the position of the nozzle head on the 20 paper.

In order to provide for interchange of nozzle head, the nozzle is provided with lugs 41, 41 and a shaft 36 passes through said lugs and the ears 16. The nozzle head carries a spring 25 42 adapted to engage a notch 43 in the shaft. Therefore, in changing nozzle heads, the spring is moved to release the shaft, the latter is pulled out and the nozzle removed, after which the shaft is again inserted in the lugs 41 and turned to permit the spring to snap into the notch 43 so that the shaft cannot become separated from the nozzle head.

Figures 7 and 8 illustrate an extension or 35 double nozzle for use with wide sheets of paper or stock to be printed. In this instance, a dummy nozzle head 45 is pivoted in the nozzle support 15 as explained under Figure 2. To this dummy nozzle head 45 is secured a bar 46 by means of screws 47. The bar is slotted as at 48, 48 and nozzle heads 49, 49 are 40 adjustably carried by the bar by screws or bolts 50.

To the rod 9 there is secured a connection 45 51 having one nipple 52 communicating with the pump and branch nipples 53, 53 connected by rubber hoses 54, 54 to the suction nozzle head nipples 55, 55.

The operation of this nozzle is as described 50 above. It is obvious that it provides a plurality of suction openings as at 56, 56 and also that the nozzle heads 49 may be replaced by a nozzle head 57, such as shown in Figures 9 and 10 which has a suction cup 58 instead of a slit such as at 25.

Figures 11 and 12 illustrate a nozzle head 60 having two suction cups 61, 61 communicating with the suction nipple 62, and two paper engaging projections 63 and 63.

During the operation of the press the nozzle hangs in the bracket 11 in the position shown in Figure 3, where it will be observed, the nozzle support 15 has dropped or slid downward in the ways 14 until the stop 22 rests on the top edge of the bracket. At the

same time, the nozzle head 35 hangs on its 65 pivots 36 in an inclined position regulated by the adjustment of the spring 29.

When, however, the nozzle head comes to rest upon the paper as in Figure 2, the parts are so arranged that the rod 9 with the bracket 70 11 continues the downward movement and the nozzle is thereby compelled to take the position shown in Figure 2 or flat down on top of the paper. The suction is then applied and the paper picked up. As the press 75 now opens, the rod 9 and bracket 11 are lifted and slide upon the nozzle support 15 until the bracket reaches the stop 22, when the nozzle support also is lifted.

During this movement and actuated by the 80 spring 29, the nozzle head has been lifted or turned on its pivots 36, which causes a rolling movement of the nozzle head and a similar and somewhat sliding movement of the top sheet as seen in Figure 3 which assists in 85 separating the sheet from the pile. Thereafter the separated sheet is conveyed to the point of application, the suction is released and the sheet drops into position.

The nozzle mechanism as herein above described possesses several important advantages and novel features. The speed with 90 which the nozzle head turns from the position shown in Figure 2 to the position shown in Figure 3 may be controlled and regulated 95 definitely to suit the paper by a careful adjusting of the spring tension by the nut 20. This is preferable to a gravity operated nozzle head such as is shown in the above named patent. Other advantages reside in the extreme simplicity of construction. 100

The foregoing is believed to be a full disclosure of this invention. It will be seen that a high degree of interchangeability and adjustability has been provided for. 105

While the invention is shown in its preferred form, yet it will be understood that changes and modifications will readily suggest themselves to persons skilled in the art and may be made without departing from the 110 principle of the invention or the scope of the appended claims.

We claim:

1. A suction nozzle of the character described comprising a nozzle support, a suction 115 nozzle head, a shaft for pivoting the latter on said support and a spring secured to said nozzle head for removably securing the said shaft to the said nozzle head.

2. A suction nozzle of the character described comprising a nozzle support, a member pivoted thereto, a plurality of suction 120 nozzle heads, and means for adjustably securing the said nozzle heads to the said pivoted member. 125

3. A suction nozzle of the character described comprising a nozzle support, a member pivoted thereto, a plurality of suction

nozzles, a slotted bar secured to said member and means for adjustably securing the said nozzle heads to the said bar.

4. A suction nozzle of the character described comprising a nozzle bracket, a nozzle support slidably mounted therein, a member pivoted to said support, a bar carried by said member, a plurality of suction nozzles,

means for securing a number of said nozzles to the said bar, a rod for carrying the said nozzle bracket, a connection piece on said rod and rubber hosing connecting the said nozzle heads individually to the said connection piece. 10
